UNITED STATES PATENT OFFICE.

JOHN AULD, OF CHICAGO, ILLINOIS.

ERASER DEVICE.

1,216,648.

Specification of Letters Patent. Patented Feb. 20, 1917.

Application filed September 21, 1914. Serial No. 862,740.

To all whom it may concern:

Be it known that I, JOHN AULD, a citizen of the United States, and a resident of Chicago, in the county of Cook and State of Illinois, have invented certain new and useful Improvements in Eraser Devices, of which the following is a specification.

My invention relates to eraser devices, particularly to eraser devices comprising an eraser and a cleaning brush.

I am aware that there are several eraser devices on the market comprising an eraser member and a brush member but in all these devices the brush member is rigid in reference to the eraser and projects radially therefrom or is tangential. In either case the brush member is more or less in the way when the eraser is to be used, and when the brush is to be used the device must be turned around, this of course taking time besides being rather inconvenient. Furthermore, such devices in which the brush member is permanently secured to the eraser member, become useless as soon as the eraser has been used up. Also in these earlier devices the brush holder is constructed usually of sheet metal, and this, together with the fact that the device becomes useless after the eraser has been used up, makes the device very expensive.

One of the important objects of my invention is to provide an erasing device comprising an eraser member and a brush member but in which such members are not permanently connected, the brush member being so constructed that it can be detachably applied to an eraser member with the advantage that when the eraser is used up the brush can be applied to another eraser member, the brush being practically indestructible. Another important object is to provide such arrangement that the members of the device are relatively adjustable in order that one member can assume various positions in relation to the other, this enabling the device to be used with greater convenience and efficiency. Another object is to simplify the construction of the brush member by constructing the bristle holding frame of ordinary wire.

The various features of my invention are clearly shown on the accompanying drawing in which—

Figure 1 is a side elevational view of my improved device,

Fig. 2 is an edge view thereof,

Fig. 3 is a sectional view on plane 3-3,

Fig. 1, showing only part of the brush holder,

Fig. 4 is an edge view showing one manner of using the device, the brush member being swung at substantially right angles to the eraser,

Fig. 5 shows another manner of holding and applying the device,

Fig. 6 is a side view showing modified construction and arrangement, and

Fig. 7 is a sectional view on plane 7-7, Fig. 6, showing only a part of the brush holder.

The device shown comprises the eraser member E and the brush member B. The eraser member is of the ordinary circular kind comprising a rubber erasing disk 10, the circular side plates 11 and 12 and the hollow rivet 13 passing centrally through the side plates and the eraser disk to provide the central opening 14.

My improved brush device comprises the holder 15 and the brush 16, the holder being preferably in the form of a single piece of wire to form the loop l and having its ends twisted together as indicated at t to clamp the bristles of the brush, the bristles being further held to the frame in any desired manner as by wire turns w. The base b of the loop is straight and is received in the groove or pocket 17 formed in one of the plates, shown in the figures as plate 11. This groove is formed by deflecting the plate outwardly along a line between its periphery and its center. Into this pocket 17 the base b of the loop l can be readily inserted by forcing the base between the rubber disk and the plate until it reaches the pocket, the remaining part of the loop being preferably circular and of a diameter slightly larger than the plate 11 as clearly shown in Fig. 1. With this arrangement the eraser and brush members are relatively adjustable and the members can be swung into parallelism or at angles with each other. This enables the eraser member to be used without being interfered with by the brush member and in such manner that the brush member can be used after an erasing operation without having first to turn the device around to get the brush into operative position. As shown in Fig. 4, the brush member may be swung to substantially right angles with the erasing member and the eraser member held in vertical position between the thumb and forefinger and with the forefinger extending through the loop l to hold the brush member

in its angular position. With this arrangement the brush is available immediately after an erasing operation by merely bending the wrist. Fig. 5 shows another manner of holding the device, the end of the forefinger being inserted through the loop to hold the brush member at right angles with the erasing member and the brush member being held at its twisted section between the thumb and middle finger. After an erasing operation the brush can be immediately used by merely lifting the hand without changing the position of the device in the hand. The device can, of course, be held in any desired manner by grasping either the eraser member alone or the brush member alone, or both together, and the members can be held in any relative position. The members can also be readily removed one from the other if it is desired to use one independently of the other.

The eraser will of course wear out comparatively quickly while the brush will outlast a great many erasers. In earlier structures where the eraser member and brush member are permanently secured together the entire device becomes useless as soon as the eraser becomes worn out. With my detachable arrangement however, as soon as one eraser is used up another eraser member can be applied to the brush member. This greatly reduces the expense as it will be unnecessary to buy an entire outfit when one eraser has been used up. The expense is also further reduced by the simple construction of the brush member, the ordinary wire frame not requiring expensive dies or machinery for its construction.

In Figs. 6 and 7 I have shown a modified arrangement. Instead of using a rivet to hold the rubber disk 10 and the side plates 11 and 12 together I use a detachable fastener 18 comprising the head *h* and the legs *i*, *i'*, the head engaging against one plate and the legs extending centrally through the plate and rubber disk and having the ends of its legs deflected against the opposite plate as clearly shown. The brush member is constructed substantially the same as in Figs. 1 to 5, but instead of having the closing plate provided with an eccentric pocket or channel, one of the plates, as for example plate 11, has the diametrically extending pocket or channel 19 provided therein for receiving the base *b* of the brush member loop *l*, the base extending between the legs *i*, *i'* of the fastening member 18 as clearly shown. This modified arrangement allows relative adjustments of the eraser member and brush member in the same manner as in the construction shown in Figs. 1 to 5. When the members are connected together in the arrangement of Figs. 6 and 7, the brush mem-

ber is locked against separation from the eraser member by the legs *i*, *i'* of the fastening member, but by straightening these legs and withdrawing the fastening member the brush member can be detached and a new eraser member readily applied thereto.

I do not of course desire to be limited to the construction and arrangements shown as other modifications are no doubt possible which would still come within the scope of my invention, and I claim the following:

1. In an erasing device, the combination with an erasing member comprising an eraser and a supporting frame therefor, of a brush member having a pivot bar clamped between said eraser and supporting frame to be free to be swung to positions at angles with the eraser.

2. In an erasing device, the combination of an eraser, supporting side plates therefor, one of said plates having a channel in its inside, and a brush member having a pivot bar for detachably engaging in said channel between said plate and eraser and adapted to be swung into positions at angles with the eraser.

3. In an eraser device, the combination with a flat eraser member, of a brush holder pivoted thereto to swing into positions at angles with the plane of the eraser member, and a brush supported by said brush holder.

4. The combination with an eraser comprising a rubber disk, side plates at opposite sides of the disk and means for holding said plates against the disk sides, a detachable frame inserted between one of said plates and the disk, said plate being grooved in its inner side for receiving a portion of the frame, said frame being held to the eraser by its engagement with the grooved plate and the friction of the rubber disk.

5. The combination with an eraser comprising a rubber disk, central side plates at opposite sides of the disk and means for holding said plates against the disk sides, of a detachable supporting frame constructed of wire and inserted at one end between one of said plates and the disk, said plate being grooved in its inner side for receiving the wire of the frame, said frame being held to the eraser by its engagement with the grooved plate, and the friction of the rubber disk, and bristles secured to the outer end of said wire frame to form a brush.

In witness whereof I hereunto subscribe my name this 18th day of September, A. D., 1914.

JOHN AULD.
